UNITED STATES PATENT OFFICE.

HORACE C. CHANDLEE, OF WASHINGTON, DISTRICT OF COLUMBIA.

DESIGN FOR A MATCH-SAFE.

SPECIFICATION forming part of Design No. 30,881, dated May 30, 1899.

Application filed March 14, 1899. Serial No. 709,094. Term of patent 3½ years.

To all whom it may concern:

Be it known that I, HORACE C. CHANDLEE, a citizen of the United States, residing at Washington, in the District of Columbia, have 5 invented and produced a new and original Design for Match-Safes, of which the following is a specification, reference being had to the accompanying drawing, forming a part thereof.

10 The leading feature of my design for a match-safe is a rectangular body portion consisting of front, side, base, and top pieces, a panel projecting forwardly from the body of the safe, having a transverse channel therein, and a longitudinal opening in the top piece.

15 In the drawing forming a part of this specification is shown a perspective view of a match-safe embodying my design, consisting of the side pieces *a* and *b*, having serrated 20 edges *a'* and *b'*, front piece *c*, having ornate-

mentation *c'*, back piece *d*, base-piece *e*, and top piece *f*, having opening *g*.

h designates a longitudinal slot, and *i* designates a panel projecting forwardly and at approximately right angles to the front piece *c* and having therein a transverse groove *k*, the central portion of which is enlarged, as shown at *l*.

m is a knob attached to the panel *i*, and *n* is a checkered surface at the forward portion 30 of the said panel.

Having thus described my invention, what I claim, and desire to secure by Letters Patent, is—

35 The design for a match-safe, substantially as shown and described.

HORACE C. CHANDLEE.
